Application May 21, 1940, Serial No. 336,323
In Mexico June 2, 1939

6 Claims. (Cl. 235—9)

The present invention relates to an improvement in machines such as registers, adding machines and the like. One object thereof has been to provide simpler mechanisms for performing various of the usual functions of machines of this class. For example, the improved totalizing mechanism of this invention, although relatively simple, can be operated with no less accuracy and rapidity than more complicated known devices for the same purpose; and machines embodying the present invention can be made and maintained in operative condition with substantial economies as compared to known types of machines for a similar purpose. Further advantages and beneficial effects in the manufacture and use of machines embodying the invention of this application will be apparent from an inspection of the following specification and the drawings appended thereto.

One embodiment of my invention as applied to a register or adding machine is shown in said drawings, wherein—

Figure 1 is a front elevation, with the casing removed to reveal the operating mechanism;

Figure 2, a fragmentary view in elevation of a front portion of the casing showing more particularly the scales or series of numeral markings by reference to which the operator of the machine is enabled to selectively condition the indicator and totalizing mechanisms to perform their intended functions;

Figure 3, a fragmentary rear view in elevation of a portion of the operating mechanism of which a front elevation appears in Figure 1;

Figure 4, a vertical cross section on the line 4—4 of Figure 1;

Figure 5, a general perspective view of one form of register and adding machine incorporating features of the invention herein described and claimed;

Figure 6, a vertical cross section on the line 6—6 of Figure 1;

Figure 7, a fragmentary view corresponding to a portion of the vertical cross section represented in Figure 4, but with certain of the operating parts in different relative positions;

Figure 8, a vertical cross section on the line 8—8 of Figure 1;

Figure 9, a vertical cross section on the line 9—9 of Figure 1 with portions broken away;

Figure 10, a fragmentary view in vertical cross section on the line 10—10 of Figure 3;

Figure 11, an enlarged view of details of a portion of the setting and totalizer operating mechanism shown in Figure 1; and

Figure 12, an enlarged view showing an intermediate position of locking devices illustrated in Figure 9.

The register and adding machine illustrated in the drawings provides among other features (1) indicator devices for exposing in predetermined positions at both front and rear of the machine numeral markings or the like representing a number or amount selected by the operator to be set up for addition in the totalizer devices, (2) totalizer devices for incorporating amounts or numbers selectively set up by the operator and means for carrying forward from one totalizer assembly to the next cumulative amounts or numbers of successively higher orders, as units to tens, ten to hundreds, etc.; (3) mechanism for resetting the totalizer devices to zero position; and (4) devices providing a positive stop to conclude each complete cycle of indicating and totalizing operation.

Said tens transfer mechanism and associated devices whereby cumulative amounts or numbers of successively higher orders are carried forward are set forth and claimed in my co-pending application, Serial No. 349,164, filed August 1, 1940, which, as to this subject matter, constitutes a continuation in part of the present application.

The embodiment of my invention shown in the drawings comprises a suitable frame including vertical side walls A and B mounted on a hollow base C, Figure 1, within which is a drawer D. A casing E of any desired or necessary shape resting on base C, encloses the walls A and B and the mechanism supported thereon. In the upper portion of casing E are front and rear openings, as windows, F and G, respectively, Figure 4, for viewing numerals presented at said openings by operation of the setting and indicator devices; and in the front wall is an opening, as a window H, for viewing numerals, representing totals, presented at said opening by operation of the setting and totalizer devices.

The front wall of casing E is also provided with vertically arranged slots K accommodating manually operated setting levers, and with a vertically arranged slot L accommodating a manually operated resetting lever.

Closely adjacent to each said slot K is a series (ten) of numeral markings 0—9 inclusive arranged parallel to longitudinal edge portions of the slot so that the setting levers may be selectively positioned by reference to said markings in a manner to be described. After each such setting, the mechanism of the machine is actuated by suitable means, such as the crank M.

Figure 1 illustrates a form of machine equipped for setting up and indicating numbers or amounts up to three digits, i. e. units, tens and hundreds. The totalizer shown, however, includes additional cylinders to accommodate cumulative totals in terms of thousands and ten thousands. Obviously such a machine may be equipped to handle numbers or amounts of any desired number of digits in the indicating and totalizing devices, or either of them.

The machine shown in Figure 1 comprises a main shaft 1 journaled at one end (left) in a hub 2 of wall A. Wall B has a hub 3 extending outwardly through casing E. A stud shaft 4, journaled in hub 3 is recessed at its inner end to journal the other (right) end of main shaft 1; and crank M is secured to the outer end of stud shaft 4 which also carries at its inner end a gear 5 forming part of a driving train of gears.

As seen more clearly in Figure 9, gear 5 meshes with gear 6 which drives gear 7, the ratios shown being 20-10-40, or such that two complete turns of gear 5 produce one complete turn of gear 7.

A gear 8 for actuating shaft 1 is secured on said shaft, as by a pin 9, Figure 1, and is rotated a quarter turn (90°) first clockwise, Figures 4 and 9, and then counterclockwise during each complete rotation of gear 7. For this purpose, a link 10, connecting said gears, is pivoted at 11 on gear 7 and at 12 on gear 8.

Gear 8 also meshes with pinion 13 loosely mounted on shaft 14 and thereby actuates a gear 15 on a cam shaft 16. A recess 17 in said shaft 15 on a cam shaft 16. A recess 17 in said shaft 15 presents a longitudinally extending shoulder 18 positioned to be engaged by a pawl 19, Figure 9, on a pawl arm 20 pivoted to gear 15 at 21 and held yieldingly in operative position by a spring 22. With gears 8, 13 and 15 in the ratio 40-20-10, it is clear that, when gear 8 initially rotates a quarter turn clockwise, gear 15 will rotate a full turn clockwise without turning cam shaft 16; but, when gear 8 is reversed a quarter turn by the driving mechanism above described, gear 15, through pawl 19, will rotate cam shaft 16 counterclockwise to actuate cams for a purpose hereinafter to be explained.

Referring to Figures 1 and 6, an axle 23 is supported at its ends in the walls A and B. Indicators cylinders 24 and 24a, each having the indicator markings 0-9 inclusive on its outer periphery and being loosely mounted on said axle 23, are rotated the necessary extent and direction to bring any selected digits thereon into position opposite the front and rear openings F and G respectively, Figure 4, the selected digits on cylinders 24 (right) Figure 1, being visible through the front opening F and those on cylinders 24a (left) being visible through rear opening G at the same time.

Each of the independently rotatable indicator cylinders 24 is secured to or driven by a gear 25 meshing with pinion 26 mounted on a shaft 27 and rotated to the required extent by a manually actuated setting gear 28 loosely mounted on main shaft 1. For this purpose, gear 28 is provided with an operating lever 29 arranged with its outer end or handle portion exposed through one of the slots K in casing E. A pointer 30 extending laterally from each lever 29 rides freely over the corresponding scale of numeral markings arranged along edge portions of slots K.

In connection with the indicator devices above described, the ratio of gear 28, pinion 26 and gear 25 is 40-20-10; and the parts are so calibrated that one tooth of gear 25 corresponds to each of

the ten numeral positions from 0-9 inclusive on cylinder 24. Thus, when a lever 29 is deflected to a position opposite "6," for example, on the units scale, cylinder 24 in the units column of the indicator is rotated to bring numeral "6" thereon into position at window F. By a suitable well known construction, cylinders 24a are connected to rotate with cylinders 24 to indicate at rear opening G the same number indicated at front opening F.

The setting or positioning of levers 29, and therefore the corresponding rotation of gears 28, as above described is also the initial step in the operation of totalizing devices including totalizing cylinders, as 31 loosely mounted on a totalizer shaft 32. For this purpose, each of said gears 28 is provided near its periphery with a laterally extending trip 33, Figure 11, the angular or set position of which determines to what extent any corresponding totalizer cylinder 31 will be rotated to add a selected number to the previously established total represented by markings visible at opening H.

As seen more clearly in Figures 1 and 4, totalizer shaft 32 has a longitudinally extending groove presenting a shoulder 34. Cylinder 31 has at one side a pawl arm 35 pivoted at 36 and provided at one end with a pawl 37 which is yieldingly pressed against the periphery of shaft 32 by a spring 38. At the other side of cylinder 31, is a gear 39 secured to said cylinder 31 and also free on said shaft 32. Gear 39, and consequently totalizer cylinder 31, is rotated by a gear 40 mounted to rotate freely on main shaft 1. Gear 40 is actuated by suitable means hereinafter described to an extent controlled by the manually set position of a trip 33 on said trip carrier or gear 28.

As appears more clearly from Figures 1, 4, 6 and 7, a pawl carrier or disk 41, loosely mounted on main shaft 1 between said setting gear 28 and said totalizer actuating gear 40, and which has a peripherally located stop 42, Figures 6 and 11, positioned in the path of movement of trip 33 on setting gear 28. Thus, when said trip carrier or gear 28 is manually rotated, as from its upper end position to an intermediate set position by deflecting lever 29 secured thereto, trip 33 immediately engages stop 42 on said disc 41 and pushes said stop along ahead of it to the angular position in which the trip is set to the desired number. A pawl arm 43 is pivoted at 44 on pawl carrier disk 41 and has a pawl 45 at its outer end and extending laterally therefrom across the periphery of the adjacent totalizer gear 40. It will be noted from Figures 6 and 11 that trip 33 on indicator and setting gear 28 also extends laterally from said gear 28 past the face of stop 42 and into the path of movement of pawl arm 43 which is controlled by a spring 46 to bias pawl 45 toward gear 40. However, during said setting movement of gear 28 and disk 41, trip 33 also engages a portion of pawl arm 43 and deflects its free end outwardly against tension of said spring 46, thereby holding pawl 45 clear of the teeth of gear 40 during said setting movement. A spring 47 secured at one end to a transverse rod 48 and at the other to pawl carrier 41 at 49, tends continuously to rotate said pawl carrier 41 counter-clockwise, Figure 6, to the extent of its movement in that direction as limited by a longitudinally extending shoulder 50 of a groove 51 in shaft 1. Actual engagement with said shoulder 50 is effected by a stop 52 extending through an opening 153 in a collar 154 secured to or forming

part of disk 41, said stop being held with its inner end yieldingly engaging shaft 1 by a spring 155.

A typical set relation of the parts above described is therefore as follows: When set as shown in Figure 4, that is with lever 29 in position at the top end of its slot, opposite units digit "9" for example, the spring pressed stop 52 of disk 41 adjacent to setting gear 28 extends into groove 51 on shaft 1 and with one edge engaging shoulder 50, thus determining one end position of rotation of said disk 41. The next lever, as 29a, Figures 1 and 11, associated with the "tens" occupies a different angular position opposite the "tens" numeral "50" for example, this being an intermediate angular position of disk 41 to which the latter has previously been moved by manual setting movement of handle 29a. The spring pressed stop 52a of the corresponding setting gear 28, i. e. the "tens" gear 28, is angularly spaced from stop 52, as shown in Figure 4. The trips 33 of these several setting gears 28 when moved by levers 29, 29a, etc. respectively, occupy corresponding different angular set positions. Thus, in being moved from the "9" position to any lower or different angular position, each trip 33 deflects a pawl 45 away from the teeth of its corresponding gear 40 and engages and bears against a peripheral stop 42 of a disk 41 as previously described, to rotate the latter to a set position where pawl arm 43 remains with its pawl 45 in raised position, i. e. out of operative engagement with any tooth or interdental space of a corresponding totalizer gear 40, Figure 4, and ready to be deflected into such operative position upon the next actuation of disk 41 by shaft 1 through crank M and the driving train previously described.

Remembering that the total rotation of shaft 1 is 90°, it will be apparent that upon the initial complete turn of crank M, shaft 1 will rotate clockwise bringing longitudinal groove 51 and shoulder 50 to the dotted line position shown in Figure 4. In so advancing, said shoulder first engages the stop 52 and advances said stop and the corresponding pawl carrier disk 41. Shoulder 50 next engages the stop 52a and its corresponding pawl carrier disk 41 and so on, the order of engagement of the several stops 52 depending on their respective angular positions. However, as soon as a carrier disk 41 starts to rotate, its pawl 45 is moved beyond and therefore disengages the corresponding trip 33 and, when thus released, is deflected by operation of spring 46, into the next interdental space on totalizer gear 40 to engage and rotate said gear with said disk 41 to the end of the 90° clockwise rotation of shaft 1.

For reasons hereinafter explained, the initial full turn of crank M is followed at each operation of the machine by a second or concluding full turn. However, during said concluding full turn of crank M, the direction of rotation of shaft 1 is counterclockwise to restore shoulder 50 to its normal initial angular position, as shown in full lines in Figures 4, 6 and 7.

During said return or reverse rotation of shaft 1, the pawl carrier disk 41 follows in rotation under tension of spring 47 until stop 52 reaches the position shown, i. e. corresponding to the "9" digit position of lever 29, Figure 4. The other carrier disk, as 41, having stop 52a, follows along with the reverse rotation of shaft 1 to the angular position indicated by said stop 52a, the "50" position. At this point, the stop 42 on carrier

disk 41 reengages trip 33 on corresponding setting gear 28. This arrests return movement of the pawl carrier disk 41 and disengages pawl 45 from the teeth of totalizer gear 40 over which the pawl 45 was riding until thus stopped and disengaged. Obviously shaft 1 continues return movement to its "zero" or initial position, regardless of the set or selected positions of any of the levers 29 and connected indicator devices, which remain as set until the operator again moves said levers 29 or any of them to different selected positions.

My improved apparatus also includes accumulator devices for rotating a totalizer cylinder representing a higher order of digits or numbers one part turn, one digit, for each full turn, ten digits, of the totalizer cylinder representing the next lower order of digits or numbers.

For this purpose, four trips 53 angularly spaced 90° extend laterally from one face of gear 40 near its periphery, so that during successive increments of rotation of said gear, each of said trips on passing a fixed point will mark the passing of ten gear teeth on gear 40 corresponding to ten digits added on the associated totalizer cylinder 31.

As shown more clearly in Figures 4 and 7, the trips 53 on each gear 40 are positioned to successively actuate a latch 54 having an upper cam edge 55 arranged in the path of said trips 53. Said latch 54 is supported and guided for vertical movement between a transverse rod 56 having an annular latch guiding groove 57 and a transverse shaft 58 having an annular latch guiding groove 59. Latch 54 has an upper slot 60 edge portions of which ride in groove 57 and a lower slot 61, edge portions of which ride in groove 59. A spring 62 having one end secured to rod 56 and the other to latch 54 normally holds the latter yieldingly in the elevated position shown in Figure 4. Latch 54 also has a laterally extending obliquely disposed detent 63 an inner inclined face of which, when in the position shown in said Figure 4, normally engages a pin 64 extending laterally from a pawl arm 65 pivoted at 66 on a rocking lever 67. Pawl arm 65 has a pawl 68 at its upper end and extending laterally therefrom (to the right Figure 3) to a position opposite and normally spaced from the teeth of that gear 40 which actuates a totalizer cylinder 31 bearing numbers of the next higher order. A spring 69 with one end secured to said rocking lever 67 and the other to pawl arm 65 normally biases pin 64 on said pawl arm 65 toward the above described yielding engagement with said inner inclined face of detent 63 on latch 54. Said rocking arm 67 is loosely mounted to rock on shaft 14 and is actuated by a cam 70, secured on cam shaft 16, against tension of a spring 71 having one end secured at the lower end of said rocking lever 67 and the other to a transverse rod 72.

As shown more clearly in Figure 7, when a trip 53 on a totalizer gear 40 engages the cam edge 55 of latch 54, the latter is pressed downwardly against tension of spring 62, thus carrying detent 63 below the level of pin 64 on pawl arm 65. Spring 69 now causes said pawl arm 65 thus released from detent 63 to rock clockwise; and pawl 68 moves into engagement with an interdental space of the next adjacent totalizer gear 40 representing numerals of the next higher order. Meanwhile, as soon as trip 53 on said gear of lower order clears the upper end of latch 54 which occurs with the passing of each tenth

tooth of said gear, the unlatching movement shown in progress in Figure 7 is completed and said latch immediately returns, under tension of spring 62, upward toward its initial or up position, shown in Figure 4. Pin 64 is now to the left of detent 63 to an extent determined in part by the angular position of pawl arm 65 when pawl 68 is moved into engagement between adjacent teeth of gear 40 by spring 69 upon release, as above described, of pin 64 from detent 63.

This release of pawl arm 65 and the consequent setting of pawl 68 into engagement with gear 40 of the next higher order is effected during the clockwise rotation of main shaft 1 previously described and which takes place during the initial full turn of crank M. During the concluding turn of said crank and the reverse rotation of main shaft 1, cam shaft 16 is rotated counterclockwise by gear 15, Figure 9, one full turn so that a cam 70 on said shaft 16 will be rotated 360°, during which movement, it deflects the lower end of rocking lever 67 against tension of spring 71 to the dotted line position and back to solid line position as shown in Figure 7. This motion of said lever 67 first imparts an upward thrust to pawl arm 65 and, through pawl 68, causes the totalizer gear 40 engaged thereby to rotate the angular space of one tooth and hence produces a corresponding rotation (one digit) of the associated totalizer cylinder 31, in addition to such independent rotation thereof as may have been imparted to it by operation of the selective totalizer actuating devices previously described. This upward thrust of pawl arm 65 carries pin 64 upwardly past the left edge or outer face of detent 63 on latch 54 and into an end position just above the level of the upper edge of said detent 63. The relative positions of pawl arm 65, lever 67 and cam 70 at this point in operation of the machine are however as shown in dotted lines in Figure 7. Meanwhile cam 70, continuing counterclockwise rotation back to its initial solid line position, permits lever 67 to be returned to its initial (solid line) position under tension of spring 71. At the beginning of this return movement, the gear engaging end portion of pawl 68 rides outwardly and over the outer end of the gear tooth next below said pawl in its gear advancing position. This first deflects pawl arm 65 counterclockwise an additional amount and so that pin 64 is thereby moved toward the right past the upper edge of detent 63 to the dotted line position, Figure 4, and then moves into its initial position (Figure 4) against the inner inclined face of said detent 63 as said lever 67 resumes its full line position. Thus for any order of numbers above units, the selected number or value is added at each operation of my improved machine to a corresponding totalizer cylinder 31 during the initial full turn of crank M; and any accumulated ten value is thereafter added thereto during the concluding full turn of said crank, so that when the latter comes to rest after each complete double turn, the totalizer cylinders will reveal, at window H, numerals representing the total of all numbers added.

As indicated more clearly in Figures 3 and 4, the cams 70 are mounted within an angle of 180° on shaft 16 in spaced and angularly staggered relation so that the "units to tens" cam 70, at the left, Figure 3, will operate first and will be followed in succession by the "tens to hundreds," "hundreds to thousands" etc. cams as rotation

of shaft 16 continues. This arrangement insures that each transferred unit of a lower order will be included in the transfer or carry of ten units of the next higher order.

An adding device according to my invention also includes mechanism for resetting the totalizer cylinders 31 to "zero" position. As shown more clearly in Figures 1 and 8, a resetting main gear 73 is loosely mounted on main shaft 1 and meshes with a gear 74 secured on totalizer shaft 31. One end of an operating handle 75 is secured to gear 73 and its other end extends through slot L in casing E. A stop 76 limits upward movement of said handle and another stop 77 limits downward movement thereof. Gear 74 has ten teeth corresponding to a like number on gear 74 and on the gears 39 attached to the totalizer cylinders 31. The previously described pawls 37 on said cylinders, Figure 4, bear a fixed radial relation to the numeral markings on the peripheries thereof, being approximately in radial alignment with the "zero" marking in each case. It will be clear that, if totalizer shaft 32, Figure 4, is rotated counterclockwise a full turn, the shoulder 34 will move into engagement with pawl 37 of each cylinder 31 and thereby rotate all of the cylinders 31 to whatever extent may be necessary to bring all of their respective "zero" markings simultaneously into transverse alignment, as viewed through opening H in casing E. This counterclockwise, Figure 4, rotation of shaft 32 is effected by pulling handle 75 downwardly to an extent limited by stop 77, Figure 8, thus rotating resetting gear 73 in the direction of the arrow thereon in Figure 8. When handle 75 is returned to "up" position as limited by stop 76, shaft 32 rotates in reverse direction but in view of the arrangement of pawl 37 on said cylinders 31 in relation to the shoulder 34 of said shaft, all of said cylinders 31 remain in reset or "zero" position.

On the down stroke of resetting handle 75 the cylinders 31 are rotated in the same direction as during normal adding operation and therefore transmit equivalent motion to the corresponding gears 49 and trips 53 thereon, with consequent effect on latch 54 and, unless prevented, on associated accumulating devices when operating handle M is next turned as above described. To prevent this operation of said accumulating devices during resetting, the pawl arms 65 are restrained from rocking when the detents 63 disengages pin 64 incident to passage of trip pins 53 across the cam edge or nose 55 of latch 54. For this purpose, deflector arms 78, Figure 4, are secured on shaft 58 and rotate therewith during rotation of resetting gear 73 to the dotted line position shown in said figure. This position is reached just before latch 54 reaches the position at which pin 63, in a normal transfer operation, is freed from detent 64. As seen more clearly in Figure 8, a crank 79 secured to said shaft 58 is yieldingly biased toward its inoperative angular position by a spring 80. A link 81 connects said crank 79 with resetting gear 73, so that when the latter is rotated in resetting, shaft 58 rotates and swings the ends of deflector arms 78 into engagement with the lower ends of corresponding pawl arms 65 which are thus restrained from swinging pawls 63 into position for engaging the teeth of associated gears 40. It will be clear from Figure 4 that, while pawl arm 65 is held from moving to the deflected position by said deflector arms 78, the pin 64 on said pawl arm remains in position to be immediately reen-

gaged by the inner inclined face of detent 63 when latch 54 returns to its "up" position, Figure 4, after passage of trip 53 across the top edge or nose 55 of latch 54 during resetting and while pawl arm 65 is in said restrained position said pawl arm 65 will not rock to engage pawl 68 with the teeth of gear 40.

Accidental or inaccurate turning of totalizer gears 40 is minimized by suitable friction or damping rollers 82 riding on the teeth of said gears and mounted on levers 83 pivoted on a transverse rod 84. Springs 85 each with one end secured on transverse rod 86 and the other end secured near one end of levers 83 hold the rollers 82 in yielding damping engagement with the teeth of their respective gears 40.

The machine shown in the drawings includes devices which automatically stop rotation of hand crank M at the end of its second or concluding turn, more particularly to prevent the operator from inadvertently recording or registering the same number twice, or otherwise interrupting or subverting the proper and intended mode of operating the machine.

As shown more clearly in Figures 1, 9 and 12, the stud shaft 4 has a collar 87 with a spirally contoured peripheral surface and a shoulder 88 interrupting said surface. Closely adjacent to said collar, a stop 89 projects inwardly from wall B. A latch lever 90, provided with a slot 91 is slidably and rotatably supported on wall B by a pivot pin 92. The upper end of latch lever 90 has a notch 93 and a laterally extending detent arm 94. A spring 95 with one end secured to wall B at 96 and the other to latch lever 90 at 97 biases said latch lever 90 toward its normal inoperative position, indicated in dotted lines in Figure 9, with notch 93 engaging stop 89 and with hook 103 disengaged from shoulder 88. As shown in Figure 10, gear 8 carries a rocking trip arm 98 pivoted at 99 and having a laterally extending trip 100 which cooperates with arm 94 in a manner to be described. A spring 101 holds trip arm 98 yieldingly against a stop pin 102 and these parts when normally inoperative occupy the positions shown in Figure 10, relatively to arm 94.

On the first 360° rotation of crank M, gear 8 initially rotates 90° clockwise, Figure 9, carrying with it to an end position indicated in dotted lines trip 100 which yields as its inclined upper edge rides against the under edge of said arm 94, (dotted line position); and the shoulder 88 of collar 87 passes clear of hook 103 (dotted line position).

On the concluding 360° turn of crank M and collar 87, counterclockwise, as viewed in Figure 9, the direction of rotation of gear 8 and trip 100 is reversed to counterclockwise, as viewed in Figure 9; and said trip 100, now prevented from yielding by stop 102, reengages arm 94 camming the same upwardly and to the left and thus rocks the upper end of latch lever 90 to the left and upwardly releasing notch 93 therefrom from stop 89. Said upper end of latch lever 90 now cannot rock to the right because its under edge is engaged by stop 89. Said latch lever 90, therefore, slides endwise upwardly across stop 89 under tension of spring 95 to an intermediate position, Figure 12, determined by the lower end of slot 91 engaging pivot 92; and hook 103 at the lower end of latch lever 90 swings toward cam surface 87 and into position to be presently engaged by shoulder 88 which in returning to the position shown in Figure 9 reengages hook 103 and thus

pulls latch lever 90 endwise downwardly until (as shown in the full line position of latch lever 90, Figure 9) the upper end of slot 91 is engaged and stopped by pivot 92. This stops further rotation of collar 87 and consequently of crank M. As soon as the operator releases said crank M, spring 95 causes hook 103 to become disengaged from shoulder 88 whereupon, by reason of the eccentric pull of spring 95 which is secured to latch lever 90 below and to the left of pivot 92, said latch lever 90 rocks clockwise, Figure 9, back to its initial inoperative (dotted line) position with notch 93 engaging stop 89. It will be apparent that latch lever 90 can not, at this stage of operation, move to the intermediate position shown in Figure 12, but must take the position just described and as shown in dotted lines in Figure 9 because, when hook 103 is released from shoulder 88, the tip end thereof can not swing inwardly (right) being obstructed in this direction by the periphery of the collar adjacent to shoulder 88. The latch lever 90, therefore, can not swing counterclockwise sufficiently for its upper end to clear the end of stop 89. The situation is different when, during return movement (left, Figure 12) of trip 100, the latter dislodges the upper end of latch lever 90 from engagement with stop 89, because this occurs at such rotative position of the collar 87 and therefore of its spiral periphery as to permit a substantial inward swing (to right) of the hook 103 when the trip 100 dislodges notch 93 from the stop 89 so that said notch 93 clears the end of stop 89, thus permitting the latch lever 90 to slide up on stop 89 to the position shown in Figure 12 under tension of spring 95.

Where my improved apparatus is embodied in a machine employed as a cash register for example, means are provided for producing a signal to show that the amount of the sale or other sum received is being "run up," i. e. recorded on the totalizer. For this purpose a bell 104, Figures 1 and 8, is struck by a clapper 105 upon each first turn of crank M, said clapper 105 being mounted on an arm 106 secured to a shaft 107 which rotates freely in one direction under tension of a spring 108. An arm 109 is secured to shaft 107 with an end portion arranged in the path of a trip 110 extending laterally from one side or face of gear 7. Thus, during rotation of said gear 7, trip 110 engages and deflects arm 109 and rotates shaft 107 a corresponding extent. When trip 110 passes and releases arm 109, shaft 107 and clapper arm 106 rotate back toward normal position under tension of spring 108 thus causing clapper 105 to strike bell 104.

Where the machine is used as a cash register and repository, the cash drawer D is locked and released by any suitable means. As shown in Figures 1 and 4, a latch lever 111 is loosely mounted to rock on shaft 107. Its lower end 112 normally lies in the path of outward movement of a portion of drawer D, to lock said drawer in closed position and against outward movement under tension of a spring 113 having one end secured to a portion of said drawer and the other end to an interior portion of a wall of the casing E. The upper end of latch lever 111 lies in the path of a cam lug 114 extending laterally from one side of gear 7, so that on each full rotation of said gear, lug 114 engages and deflects lever 111 to raise the lower end 112 out of locking position, thus releasing drawer D which is then moved outwardly by spring 113. On its return to closed position the rear edge of the rear wall

of drawer D bears upwardly against the lower inclined edge 115 of lever 111 and deflects said lever in passing to the normal locked position as shown in Figure 4.

I claim—

1. Register device comprising a rotatably mounted totalizer wheel, a manually adjustable trip, a rotatable pawl carrier arranged and adapted to be positioned normally by reference to the position of said trip, a pawl mounted on said carrier in position to be deflected out of operative position by said trip, means operable independently of said trip for rotating said carrier and therewith advancing said pawl, and a gear operatively connected to actuate said totalizer wheel and positioned to be engaged by said pawl when the latter is advanced by said trip whereby said gear is rotated with rotation of the pawl carrier by said independently operable means to an extent determined by the selected operative tripping position of the trip.
2. Register device comprising a rotatably mounted totalizer wheel, a manually adjustable trip, a rotatable pawl carrier, a pawl mounted thereon and biased toward operative position and normally held in inoperative position by said trip, means for rotating said carrier and therewith advancing said pawl into position to be released from said trip, and a gear operatively connected to actuate said totalizer wheel and positioned to be engaged and actuated by said pawl when the latter is released from said trip, whereby said gear is rotated with rotation of the pawl carrier beyond said trip to an extent determined by the operative tripping position of the trip.
3. Register device comprising a rotatably mounted totalizer wheel, a manually adjustable trip, a main shaft, a pawl carrier mounted to be rotated in one direction by rotation of said shaft and biased in the opposite direction by a spring, a pawl mounted on said carrier and biased toward operative position and releasably held in inoperative position by said trip, means for rotating said shaft and therewith said carrier to advance said pawl into position to be released from said trip, and a gear operatively connected to actuate said totalizer wheel and positioned to be engaged and actuated by said pawl when the latter is released into operative position from said trip, whereby said gear is rotated with rotation of the pawl carrier and said shaft to an extent determined by the operative tripping position of the trip.
4. Register device comprising a rotatably mounted totalizer wheel, a manually adjustable trip, a main shaft, means for rotating said shaft in a predetermined extent in one direction and then the same extent in the opposite direction, a pawl carrier mounted thereon and adapted to be rotated by said shaft in said first direction, a spring arranged to bias said carrier in the opposite direction, a pawl mounted on said carrier and nor-
5. In a machine of the class described, the combination of a totalizer actuating gear, a rotatable pawl carrier having a pawl normally biased to engage and rotate said gear during rotation of said carrier in one direction and adapted to ratchet over said gear during rotation of said carrier in the opposite direction, a rotatably adjustable trip carrier mounted coaxially with said gear and said pawl carrier, a trip on said carrier movable therewith to a set position and operatively connected to position said pawl carrier at a corresponding set position, and means for independently rotating said pawl carrier in one direction beyond said set position to advance said gear, and in the opposite direction, to return said carrier back to said set position while said pawl ratchets over said gear.
6. In a machine of the class described, the combination of a totalizer shaft having a longitudinally extending shoulder, a totalizer wheel mounted to rotate on said shaft, a main shaft having a longitudinally extending shoulder, a gear loosely mounted on said main shaft and connected to drive said totalizer wheel, a pawl carrier mounted on said main shaft to rotate in one direction and spring biased in the opposite direction, spring actuated means operatively arranged between said pawl carrier and said shoulder on the main shaft for connecting said pawl carrier to rotate in one direction with said main shaft, a stop on said pawl carrier, a pawl on said pawl carrier normally biased to engage said gear, a trip manually movable for setting to different angular positions and having a portion arranged and adapted to engage said stop and a portion arranged and adapted to deflect and hold said spring pressed pawl out of engagement with said gear during setting movement of said trip, and means for actuating said main shaft in one direction and thereby said spring actuated connecting means to rotate said pawl carrier initially to release said stop and to release said pawl from engagement with said trip into engagement with said gear to thereby rotate said totalizer wheel a predetermined angular extent, and then in a reverse direction, to permit return movement of said pawl carrier whereby said pawl and said stop reengage said trip in its last set position, said pawl ratcheting over said gear during said return movement.

HILARIO MORENO BANUELOS.
